UNITED STATES PATENT OFFICE

2,318,099

TRIMMING MACHINE

William Thomas Buckingham Roberts, Leicester, England, assignor to United Shoe Machinery Corporation, Flemington, N. J., a corporation of New Jersey

Application December 22, 1941, Serial No. 423,894
In Great Britain January 23, 1941

5 Claims. (Cl. 12—83.5)

This invention relates to trimming machines of the type illustrated and described in United States Letters Patent No. 2,260,483, granted October 28, 1941, on an application filed in my name. The purpose of such a machine is to sever surplus materials from the lasting margin of the upper and the lining of a partially fabricated McKay shoe on a last, particularly at the toe end and at the sides of the forepart adjacent to the toe end.

For the purpose above stated the machine is provided with a cutting head having a U-shaped recess to receive the toe end of a shoe, and with power-operated trimming means including a knife that lies initially over the ball portion of a shoe and travels lengthwise of the shoe away from the heel end thereof and across the cutting bed on which the materials to be trimmed lie outspread. The organization illustrated in the aforesaid patent also includes a pair of spreading members operated automatically to travel ahead of the knife and in the same general direction to turn out the margin of the upper and the lining at the toe and lay it on the cutting bed in readiness for the trimming operation.

When the machine, organized as aforesaid, is used to operate on a boot having an extremely thick upper, for example, a military boot, one pair of spreading members arranged to turn out the margin at the toe end is not also capable of turning it out at points adjacent to the tip-line, particularly if the shoe has been previously side-lasted, because the lasting margin at the sides is secured to the insole by lasting tacks, two of which are adjacent to the tip-line. Since extremely thick upper leather can be creased only by direct application of a powerful force, and since the aforesaid spreading members are arranged to perform their spreading function at the toe end of a shoe, the portions of the lasting margin that extend from these spreading members to the nearest lasting tacks stand nearly if not quite erect instead of being folded and creased in the region of the tip-line. Under these conditions the erected portions may project into the path of the trimming knife, only to be cut off and leave too little material in the lasting margins at those points.

To avoid the result last pointed out, the present invention provides a power-operated mechanism including a pair of secondary spreading members arranged to turn out the side lasting margins abruptly in the region of the tip-line and press them against the insole with sufficient force to crease them and maintain them entirely out of the path of the trimming knife.

The secondary spreading members supplement the spreading effect of the spreading members that operate on the toe portion of the lasting margin, and in the organization hereinafter de-

scribed the pair for the toe act first and the pair for the sides act immediately thereafter.

Referring to the drawings,

Fig. 1 is a right side elevation of a trimming machine embodying the present invention. In this view the outlines of former elements are represented by dot-and-dash lines;

Fig. 2 is a similar elevation on a larger scale of that portion of the machine in which the secondary spreading mechanism is concentrated;

Fig. 2A is a sectional view of a portion of a shoe located in the machine in readiness for the operation to be performed;

Fig. 3 is a vertical section, viewed as in Figs. 1 and 2, of the mechanism for operating the primary spreading members;

Fig. 4 is a top plan view of the upper spreading assemblage;

Fig. 5 is a cross-section indicated by line V—V in Fig. 2. This view includes the secondary spreading members and the knife-carriage assemblage;

Fig. 6 is a vertical section (see line VI—VI in Fig. 5) of a connection by which one of the secondary spreading members is shifted from, and returned to, the path of the trimming knife;

Fig. 7 is a rear elevation of the cam assemblage for operating the secondary spreading members;

Fig. 8 is a cross-section (see line VIII—VIII in Fig. 7) of a cam coupling;

Fig. 9 is a top plan view including the forepart of a shoe in dotted lines and the cutting bed assemblage partly in section; and

Fig. 10 is a top plan view of the forepart of the shoe after the lasting margin thereof has been spread around the toe and creased adjacent to the foremost side-lasting tacks.

Referring to Figs. 1 and 5, a flat disk knife 10 having a circular cutting edge nearly five inches in diameter is affixed to a carrier 11 that travels in a straight line from the front toward the rear of the machine to perform the trimming operation and returns to its initial position near the front before the machine comes to rest. Grooved runners 12 affixed to the carrier are arranged to slide on track members 13 affixed to the frame 14 of the machine. Power operated mechanism for reciprocating the carrier 11 comprises a pair of links 15, a lever 16, an eccentric strap 17, an eccentric 18, and a cam shaft 19 to which the eccentric is affixed. The lever 16 is mounted on a fulcrum rod 24. A continuously rotating pulley 20 that constitutes the driving member of a clutch is mounted on a power shaft 21 and is rotatable relatively thereto when the clutch is disengaged but the driven member of the clutch, concealed behind the pulley, as viewed in Fig. 1, is affixed to the shaft. Rotation of the shaft 21 is communicated to the cam shaft 19 by

spur gears 22 and 23. All the parts are represented in their initial position in this figure.

The operating stroke of the knife 10 carries it part way across, but not entirely across, a stationary cutting bed indicated at 25 in Fig. 1. The construction of the cutting bed is better illustrated in Figs. 3 and 9. As shown in Fig. 9 the bed comprises two blocks 26 connected by a hinge pin 27 and mortised one into the other to provide, in effect, an uninterrupted U-shaped work-supporting surface and a correspondingly shaped recess to receive the toe end of a shoe represented in dotted lines. The outer U-shaped boundary of the blocks 26 is embraced by a thin flexible strip 28 of steel, the upper edge of which lies in the plane of the knife 10 to provide a shearing element across which the cutting edge of the knife may travel to sever all surplus material that may lie on or project beyond the strip. The blocks 26 are secured respectively to bolster blocks 29 by screws 30. Referring to Fig. 3, the blocks 29 are seated on a flat plate 31 and the latter is seated upon and affixed to a portion of the frame 14. A retaining plate 32 seated on the blocks 29 is connected to the plate 31 by screws 33, but bushings 34 are interposed between the plates 31 and 32 to prevent clamping the blocks 29 when the screws are set up tightly. It is, therefore, possible to adjust the blocks 29 and 26 with angular movement about the axis of the hinge pin 27 for the purpose of regulating the width of the U-shaped recess in accordance with the width of the toe portion of a shoe.

The means shown in Fig. 9 for adjusting the sections of the cutting bed comprise a hand wheel 35, a stem 36, bevel gears 37 and 38, a screw-shaft having a right-hand thread 39 and a left-hand thread 40 and correspondingly threaded nuts 41 and 42. These nuts are of external cylindrical form and are nested in correspondingly shaped sockets formed in the blocks 29 in which they may turn slightly with regard to the angular movements of the blocks. The stem 36 has a bearing in a boss 43 formed on one of the blocks 29. A thrust collar 44 affixed to the stem 36 is provided with a series of grooves or depressions 45 any one of which may be brought into register with a spring follower 46 arranged in a socket in the boss 43. The follower and the depressions 45 serve to retain the sections of the cutting bed in different positions of adjustment without preventing changes of adjustment when moderate force is used to turn the hand wheel 35.

The forepart of a side-lasted shoe of the McKay type is represented in Figs. 5 and 9. The last 50 is provided, as usual, with a bottom plate 51 of steel to clench the lasting tacks driven through the lasting margins of the upper 52, the lining 53 and the insole 54. As shown in Fig. 9 the lasting margins have been secured to the insole along both sides of the forepart by tacks 55 of which those nearest the toe end of the shoe are adjacent to the tip-line thereof. The toe tack usually driven in the middle during the pulling-over operation should be pulled out before the shoe is placed in the recess of the cutting bed because the trimming operation hereinafter described requires turning out the lasting margin of the upper and the lining and spreading it on the cutting bed prior to the severing operation to be performed by the knife 10.

As in former machines of this general type, the machine represented in this application is provided with means for locating a shoe in the desired position and for holding it firmly against

displacement during the operation of the knife 10. Accordingly, when the operator has placed the toe end of a shoe in the U-shaped recess of the cutting bed as represented in Fig. 9, he will first depress a treadle, not shown, by which a forepart jack will be raised to support the toe end of the shoe in the desired relation to the path of the knife 10. As shown in Fig. 5, the forepart jack comprises a roll 57 and a post 58 by which it is carried, the post being also indicated in Fig. 1 and guided by a stationary bracket 59 through which it may slide. When the forepart is thus jacked its bottom is located by stationary gauges, one of which is indicated at 60 in Fig. 5.

Referring to Fig. 1, a heel-engaging member 62 is formed and operated as in former machines to exert pressure lengthwise of the shoe for the purpose of maintaining the toe end against the blocks 26 of the cutting bed with considerable force. Since the mechanism for operating the clamping member 62 is like the corresponding mechanism illustrated and described in the patent mentioned above, it will presumably suffice for present purposes to state that when a hand lever 63 is raised, the first effect thereof is to move the clamping member 62 in a direction to apply clamping pressure to the shoe, and that further upward movement of the hand lever, after the clamping member 62 has been arrested by the shoe, will trip the clutch comprising the driving member 20. In this manner automatic operation of the several mechanisms hereinafter described and including that of the knife 10 is initiated to produce a complete cycle, at the conclusion of which the several mechanisms are arrested in their initial positions.

Referring to Fig. 3, one of the cams carried by the shaft 19 operates a pair of primary spreading members 64 with to-and-fro movements lengthwise of the shoe, as in former machines of this type. The cam 65 for this purpose engages a cam roll 66 carried by a lever 67. The lower end of the lever is mounted on a fulcrum rod 68 (Fig. 1) and the upper end thereof is connected with a slidable carriage 69 by a link 70. The primary function of the spreading members 64 is to bend out the lasting margin of the upper 52 and the lining 53 from the point of the toe with movement away from the heel end of the shoe, but these spreading members are mounted on pivot pins 71 (Fig. 4) about which they may swing away from each other to bend opposite portions of the lasting margin away from the sides of the toe portion. For the latter purpose, the shaft 19 is provided with a cam 72. The members 64 are connected to the carriage 69 (Fig. 3) by a block 73 which receives a slight movement up and down as in former machines of this type. For the purpose of moving the members 64 toward and from each other they are connected by individual rods 74 with a bell crank lever 75 (Figs. 3 and 4) the fulcrum 76 of which is carried by the carriage 69. A roll 77 carried by the lever 75 is arranged to travel to and fro on an arm 78 that receives up-and-down movements from the cam 72. A roll 79 carried by the arm 78 bears on the perimeter of the cam. The fulcrum 80 of the arm 78 is stationary. A compression spring 81 exerts its force against the lever 75 to close the spreading members 64 when the arm 78 descends.

The various motions of the spreading member 64, described in detail in a former disclosure, are as follows: these spreading members stand ini-

tially in the positions shown in Figs. 3 and 4, about midway between their limits of travel lengthwise of the shoe and raised far enough to clear the upstanding lasting margin at the toe end of a shoe that has been jacked and secured in the desired position for operation of the machine. In the course of a cycle they first move toward the heel end of a shoe far enough to overhang the forepart; they swing toward each other about their pivot pins 71; they descend into engagement with the insole; they are shifted away from the heel end far enough to bend out the lasting margin from the toe end and lay it over the corresponding area of the cutting bed; they are separated with movement about their pivot pins 71 to bend out portions of the lasting margin widthwise from the sides of the toe portion; they are depressed against the cutting bed to compact the outspread portions of the margin; they are immediately raised far enough to clear the portions of the outspread margin that may overlie the flexible steel strip 28; they move again away from the heel end to clear the path of the knife 10; and they finally return to their initial positions.

If the vamp of the shoe is particularly thick and therefore highly resistant to bending, the portions X of the lasting margin (Figs. 5 and 9) between the primary spreading members 64 and the foremost lasting tacks 55 will stand up from the insole and might, in the absence of being bent out and down adjacent to those tacks, be cut by the knife 10 and leaves less than the desired width of lasting margin for the subsequent toe-lasting operation. Therefore, to guard against such cutting, the present invention provides the supplemental margin-spreading mechanism now to be described.

This mechanism comprises a pair of secondary spreading members 85 (Figs. 4, 5 and 6) each provided with a serrated block 86 that constitutes a claw. Considering Fig. 5, the members 85 are initially raised and in close relation one to the other but spaced apart far enough to clear the insole gauge 60. Their first movement is downward under the influence of springs by which they are pressed against the insole. When this contact has been established they are moved apart, still in contact with the insole, and their claw portions 86 are thus brought into engagement with the portions X of the lasting margin that extend from the foremost lasting tacks 55 to the tips (now separated) of the primary spreading members 64. These portions X of the margin, whether previously erected or not, will be bent outwardly, creased and pressed down by the claw members 86 which will ride over them and depress them below the path of the knife before the latter has advanced far enough to do any cutting.

Still referring to Figs. 4 and 5 the outer ends of the members 85 are connected to individual arms 87 by pivot pins 88. The arms 87 are initially drawn toward each other by a tension spring 89 connecting them. Their rear ends are mounted on pivot pins 90 that extend through rockers 91 arranged in alined bearings in blocks 92 secured to the frame 14. The rockers 91 provide for movements up and down of the arms 87 while the pivot pins 90 provide for movements toward and from each other. Each rocker 91 includes a portion 93 (Fig. 2) that underlies and engages a lug 94 formed on the corresponding arm 87 for the purpose of lifting the arm against the tension of a spring 95. Each rocker also

includes a portion 96 in which a hemispherical socket is formed for the reception of one end of an operating pin or strut 97. Both ends of each pin 97 are hemispherical and the upper end of each is seated in a hemispherical socket formed in a screw 98. These parts provide universal joint connections for communicating downward movement to the portions 96 from a double operating lever 99 in which the screws 98 are secured. The lever 99 is in the form of a yoke and is arranged to rock on a stationary rod or fulcrum pin 100. An arm 101 of the lever 99 carries a roll 102 that cooperates with a cam 103. This mechanism produces up-and-down movements of the claw members 86.

The mechanism for moving the claw members away from each other in opposition to the spring 89 is derived from a cam 104 that cooperates with a roll 105 carried by an arm 106. This arm is a part of a double lever 107 in the form of a yoke that straddles the lever 99, and both are mounted on the same fulcrum pin 100. Links 109 (Fig. 4) provide individual connections between the lever 107 and the arms 87. The connections between the links and the arms are provided by swivel studs 110 and those between the links and the lever 107 are provided by swivel studs 111. Referring to Fig. 2, when the arm 106 is raised by its cam 104, the arms 87 are operated to draw the secondary spreading members 85 away from each other in opposition to the force of the spring 89. This secondary spreading occurs immediately after the primary spreading members 84 have been separated to start the sidewise spreading of the lasting margin.

The cams for operating the spreading members 85 (Fig. 2) derive their rotation from the cam shaft 19 through a train of connections comprising helical gears 112 and 113, an upright shaft 114, and helical gears 115 and 116. Referring to Fig. 7, the helical gear 116 and the cams 104 and 103 are arranged in end-to-end relation on a horizontal spindle 117 and they may rotate without driving the spindle. A tongue-and-groove coupling 118 serves to transmit rotation from the gear 116 to the cam 104. As shown in Fig. 8, a driving segment 119 of the hub of the cam 104 normally engages a driven segment 120 of the hub of the cam 103 while a connecting spring 123 maintains a gap 121 between these segments. Nevertheless, at one stage in their cycle of rotation, that is, when the roll 102 drops from the high portion of the cam 103 into an abrupt recess 122 (Fig. 2) this roll causes the cam 103 to run ahead of the cam 104 to the extent afforded by the gap 121. The purpose of this momentary acceleration of the cam 103 is to gain a little time in which the claw members 86 may operate after the primary spreading members 84 have opened but before the knife 10 has advanced far enough to cut the lasting margin. Once the cam 103 has been thrown ahead by the roll 102 it pauses momentarily while the leading edge of the segment 119 regains its driving engagement with the segment 120 as shown in Fig. 8.

Referring to Figs. 4, 5, and 6, the to-and-fro movements of the knife carrier 11 swing the spreading members 85 about their pivots. For this purpose a thin curved strip 126 of steel is fastened to a supporting strip 127 secured to the carrier 11. The strip 126 is spaced a short distance from a curved series of work-pressing members 128 also carried by the carrier 11. The curved channel between the members 128 and the strip 126 is occupied by upstanding lugs 125

formed on the claw members 86, but these lugs are loosely confined in the channel and may travel lengthwise thereof. When the knife is traveling toward the cutting bed and the claw members 86 are being separated to bend out and press down the portions X of the lasting margin, the pressing members 123 engage the lugs 125 and thus swing the members 85 about their pivot pins 88. The cutting edge of the knife is thus protected from contact with the claw members 86. When the knife travels in the reverse direction, after completing its cutting stroke, the thin strip 126 engages the lugs 125 to swing the members 85 to their initial positions. These sliding connections between the knife carrier and the claw members enable the latter to operate in close relation to the cutting edge of the knife without being actually engaged thereby.

Referring to Fig. 1, and recalling that the knife 10 is reciprocated by the eccentric 18, the initial position of the eccentric is such as to provide an interval of time for the margin-spreading movements, first of the primary spreading members 64 and thereafter of the secondary spreading members 85, before the knife is advanced to the extremities of the cutting bed 25. It was mentioned in the description of the motions of the primary spreading members 64 that they pause momentarily over the cutting bed after they have been separated to produce the primary sidewise spreading of the lasting margin and that during this pause they are depressed to compact the outspread margin against the cutting bed. It is during this momentary pause and the compacting operation that the secondary spreading members drop into engagement with the insole and then move apart to complete the sidewise spreading of the lasting margin.

Having thus described my invention, what I claim as new and desire to secure by Letters Patent of the United States is:

1. A trimming machine comprising a cutting bed having a U-shaped recess to receive the toe end of a partially fabricated shoe on a last, means arranged to support a shoe in cooperative relation to said cutting bed, power-operated mechanism including work-engaging means movable away from the heel end of the shoe and across said cutting bed to spread the toe margin of the shoe upper on said bed, power-operated mechanism including a pair of supplemental spreading members movable away from each other widthwise of the shoe in paths adjacent to the insole and near the tip-line thereof to fold out the side lasting margins of the lining and the upper, and power-operated cutting mechanism arranged to sever surplus materials from the outspread portions of the lining and the upper lying on said cutting bed.

2. A trimming machine comprising a cutting bed having a U-shaped recess to receive the toe end of a partially fabricated shoe on a last, means arranged to support a shoe in cooperative relation to said cutting bed, power-operated mechanism including work-engaging means movable away from the heel end of the shoe and across said cutting bed to spread the toe margin of the shoe upper on said bed, a pair of members arranged to bear on the insole adjacent to the tip-line, resilient means by which said members are pressed against the insole, power-operated mechanism by which said members are moved away from each other widthwise of the shoe to fold

out the side lasting margins of the lining and the upper, and power-operated mechanism arranged to sever surplus materials from the outspread portions of the lining and the upper lying on said cutting bed.

3. A trimming machine comprising a cutting bed having a U-shaped recess to receive the toe end of a partially fabricated shoe on a last, means arranged to support a shoe in cooperative relation to said cutting bed, power-operated mechanism including work-engaging means movable away from the heel end of the shoe and across said cutting bed to spread the toe margin of the shoe upper on said bed, a pair of claws arranged to engage the side lasting margins of the upper and the lining adjacent to the tip-line, a pair of carriers by which said claws are supported and to which they are connected by pivots extending heightwise of the shoe, resilient means by which said claws are pressed against the insole between said lasting margins, power-operated mechanism by which said carriers are moved to carry said claws away from each other widthwise of the shoe and thereby bend said lasting margins outwardly, power-operated mechanism including a knife and a knife-carrier movable away from the heel end of the shoe and across said cutting bed to sever surplus materials of the upper and the lining lying thereon, and means connecting said knife-carrier and each of said claws individually to swing the latter about said pivots and thereby clear them from the path of the knife during the cutting stroke of the latter and return them to that path during the return stroke of the knife.

4. A trimming machine comprising a cutting bed having a U-shaped recess to receive the toe end of a partially fabricated shoe on a last, means arranged to support a shoe in cooperative relation to said cutting bed, a pair of primary spreading members arranged to turn out the toe margin of the upper and the lining and lay it on said cutting bed, a pair of secondary spreading members arranged to turn out the side margins of the upper and the lining adjacent to the tip-line, power-operated means by which said pairs of spreading members are operated successively in timed relation to turn out said toe margin and thereafter said side margins, and power-operated means including a cutter arranged to sever surplus materials from the outspread portions of the lining and the upper lying on said cutting bed.

5. A trimming machine comprising a cutting bed having a U-shaped recess to receive the toe end of a shoe on a last, means arranged to secure a side-lasted shoe in cooperative relation to said cutting bed, power-operated mechanism including work-engaging means movable to bend the toe margin of the upper and the lining away from the heel end of the shoe and lay it on said cutting bed, power-operated mechanism including work-engaging means movable to fold out and crease those portions of the lasting margin that lie adjacent to the side-lasted portions thereof and press them against the insole, and power-operated cutting mechanism including a knife arranged to travel over and clear the portions of the lasting margin so creased and thereafter sever surplus portions of the margin lying on said cutting bed.

WILLIAM THOMAS
BUCKINGHAM ROBERTS.
